Application December 9, 1947, Serial No. 790,502

14 Claims. (Cl. 343—121)

1

This invention relates to radio direction finders of the type producing an indicating voltage dependent on the deviation of the direction of signal arrival from the null or reference direction of a directional antenna, and the principles of this invention may be applied to direction finders employing manual or automatic orientation of the directional antenna as well as to those deriving the indicated bearing by comparison of the indicating voltages derived from a plurality of fixed directional antennas.

The object of this invention is to reduce or substantially eliminate the production of directional indicating voltage from atmospheric or other noise of random character which normally causes considerable error in the indicated bearing.

Another principal object of the invention relates to a direction finder system of the type employing a loop antenna and a sense-of-direction antenna and an associated balanced modulator, which are connected to a superheterodyne radio receiver without requiring the usual phasing circuit between the said modulator and the input to the receiver.

Another object relates to a radio direction finder system employing a loop antenna and a sense-of-direction antenna with a balanced modulator between the loop antenna and the radio receiver and whereby the natural quadrature phase relation between the voltages from the two antennae is utilized so that the sidebands from the modulator are in phase with respect to the carrier from the sense-of-direction antenna. The sum of the carrier and sideband signals in the intermediate frequency section of the radio receiver appears as a phase-modulated wave, the modulation sidebands of which are not so readily destroyed by noise overloading, as are those associated with amplitude modulation. In the conventional direction finder arrangement, a special phasing circuit, which is difficult to design and set up, is required between the usual balanced modulator and the superheterodyne radio receiver so as to constitute amplitude modulation rather than phase modulation of the sense-of-direction signal.

A feature of the invention relates to a method of combining the signals from a directional antenna and a non-directional antenna by heterodyning the signal from one antenna with a frequency derived from a local beat frequency oscillator to produce a beat note which is used to modulate the signal from the other antenna. This beat note is subjected to a predetermined

2

time delay before effecting said modulation and the resultant modulated signal is passed through the usual radio receiver circuits to produce the bearing indication voltage under control only of the components in the receiver output which are of the same frequency as that of said local beat frequency oscillator.

Another feature relates to a receiving arrangement for a direction finder of the type employing a directional antenna and a non-directional antenna, and comprising a superheterodyne radio receiving arrangement for producing an intermediate frequency signal which is the resultant of modulation of the carrier signal from the non-directional antenna by the output of a balanced modulator which modulates the carrier from the directional antenna with a locally-generated beat frequency. Said resultant intermediate frequency is of the same frequency as said local beating frequency so that it can be applied together with the local beat frequency to a detecting circuit of the "product detector" type to produce a bearing indication signal which is instantaneously proportional to the product of the two applied voltages, and the product detector is connected to a filter arrangement for by-passing all except the uni-directional components of the output.

A further feature relates to a radio direction finder of the type employing a loop antenna and a sense-of-direction antenna, both of which feed a superheterodyne radio receiver, the sense-of-direction signal being applied directly to the receiver and the loop signal being modulated in a balanced modulator with a local oscillation, characterized in the novel features that the said local oscillation is derived from a beating oscillator whose output is mixed with a selected intermediate frequency sideband from the receiver to produce said local oscillation. A product detector is also provided and is arranged to be fed with said beating frequency and with a sideband intermediate frequency from the receiver which sideband is equal in frequency to said beating frequency. In order to facilitate the amplification of the resultant bearing indication signal from the product detector, the phase of said local oscillation is continuously reversed at a predetermined rate by means of a switch, and the output of the product detector is also subjected to mechanical rectification in synchronism with the operation of said switch.

A still further feature relates to the novel arrangement and interconnection of parts which

cooperate to provide a more reliable radio direction-finding arrangement.

Other features and advantages not specifically enumerated, will be apparent after a consideration of the following detailed descriptions and the appended claims.

In the drawing.

Fig. 1 is a schematic illustration, in block diagram form, of a conventional radio direction finder arrangement which is used in explaining the present invention.

Fig. 2 is a schematic illustration, also in block diagram form, of one embodiment of the invention.

Fig. 3 is a schematic wiring diagram of a modification of Fig. 2.

Fig. 4 is a schematic diagram of a typical product detector that is used in the embodiment of Figs. 2 and 3.

The usual direction finder circuit, such as is commonly used in airborne automatic direction finders, is shown in Fig. 1. The directional signal f_s from loop 1 is modulated in balanced modulator 2 by voltage from a low frequency oscillator 8 of frequency f_a . The output of modulator 2 is passed through radio-frequency phasing circuit 3 and applied to the input of a superheterodyne radio receiver 4 together with reference signal from sense antenna 5. The intermediate frequency output of the receiver is rectified in second detector 6. The output of detector 6 contains, in addition to the modulation components of the original signal f_s , components of frequency f_a produced in detector 6 by demodulating against carrier signal f_s from antenna 5, the double sideband derived by modulating in balanced modulator 2 the signal f_s from antenna 1 with the local oscillations f_a . Phasing circuit 3 is required so that the modulation products from modulator 2 will be phased properly with respect to the reference signal from antenna 5 so as to constitute amplitude modulation rather than phase modulation of the reference signal as required in detector 6, since the signal from antenna 1 is in phase quadrature with that from antenna 5. The components of frequency f_a from detector 6 are selected and amplified in audio frequency amplifier 7a and thence in the audio frequency amplifier 7 which selectively amplifies frequency f_a , this selectively amplified frequency is then combined in the device 9 with voltage from oscillator 8 to produce the directional indication. Device 9 may, for example, consist of a two-coil electrodynamometer instrument which produces the directional indication directly whenever it receives in one coil components from amplifier 7 of the same frequency as the frequency components from oscillator 8 in the other coil. Usually device 9 is some circuit commonly called a phase detector or product detector which produces an output voltage approximately proportional to the product of the two A. C. input voltages and the cosine of the phase angle between them. Thus, in Fig. 1, the output of device 9 is unidirectional (D. C.) and is shown connected to terminals 11 through filter 10. The output at terminals 11 will be zero, of course, when loop 1 is oriented for zero signal pickup, and the polarity of the output will depend on the angular deviation of loop 1 from this null orientation, since opposite deviations pick up signals in opposite sense. Thus, during one instant in the modulation cycle when the signal from the loop for a positive deviation would add to the signal from the sense antenna in detector 6, re-

versing the sense of the deviation would cause it to subtract instead, thus resulting in a 180° phase reversal in the f_a components from detector 6 as referred to the phase of the oscillations from oscillator 8, and consequent reversal of the polarity at 11. Hence terminals 11 can be connected to a zero-center D. C. instrument for indicating the sense of the bearing deviation, or to a servomotor control circuit for automatic orientation of the loop to the null position.

Even through the loop be oriented for zero signal pickup, there may be noise arriving from some direction other than that of the signal and which is picked up by loop 1 as well as by sense antenna 5. During moments when this noise voltage in detector 6 is stronger than the signal voltage, the D. C. output of detector 6 will consist mostly of rectified noise voltage. During one part of the modulation cycle in modulator 2, the noise voltage from loop 1 will add to that from antenna 5, and during another part it will subtract, so that the output of detector 6 will contain components of frequency f_a derived from the noise, resulting in a spurious D. C. indicating voltage at terminals 11 of polarity determined by the direction of arrival of the noise. This in turn will affect the servo system and cause misorientation of the loop, or "pulling" of the indicated bearing by the noise.

If the noise were stronger than the signal only occasionally, its effect could be reduced materially by a limiting circuit which effectively stops the production of indicating voltage whenever the total I. F. signal exceeds a threshold value set equal to that of the signal. Unfortunately, however, severe atmospheric noise, after passing the selective circuits of the receiver, is not usually of peaked or intermittent character and might be stronger than the signal practically all of the time. Limiting action would then disable the circuit entirely and prevent it from taking a bearing. Hence in accordance with one phase of the invention the receiver circuits are designed specifically to avoid severe limiting action and overloading, so that indicating voltage will be produced at least part of the time even under comparatively severe noise conditions, and additional means are provided for reducing the production of spurious indicating voltage from the directional noise intercepted, such an arrangement is illustrated in Fig. 2, wherein the parts which are the same as those of Fig. 1 are designated alike.

In Fig. 2, loop modulator 2 is actuated by a beat note of frequency f_b derived in mixer 12 by heterodyning the I. F. signal of frequency f_s from receiver 4, against the output of I. F. beat-frequency oscillator 13. The beat-not output of mixer 12 may be selected and amplified by selective amplifier 14, the output of which is applied as modulating voltage to balanced or carrier suppressing modulator 2. Selectivity in amplifier 14 is not essential to the anti-noise feature of this invention, however. If the frequency of oscillator 13 is lower than that of the I. F. signal, for example, ($f_b = f_s - f_a$), modulation of the loop signal by f_b produces two sidebands spaced in frequency from that of the signal by the frequency interval f_b . These sidebands appear in the I. F. circuits of the receiver 4 as components of frequency $f_s + f_b$ and $f_s - f_b$, respectively. Since $f_s - f_b = f_a$, one of these is of exactly the same frequency as that of oscillator 13, is independent of receiver tuning, and can produce the indicating voltage by various selecting means, one of which is indicated as

device 15. Device 15 here takes the form of a product detector, having a pair of input circuits and a single output circuit with I. F. output from the receiver 4 applied to one input circuit, and beat frequency oscillator voltage from oscillator 13 applied to the other input circuit. The D. C. output of device 15 is then applied to terminals 11 through filter 10. Various forms of product detector suitable for use in Fig. 2 are disclosed in my copending patent application Serial No. 790,501, filed on even date herewith, and a typical one of such detectors is illustrated in Fig. 4 hereof. Thus as shown in Fig. 4, the product detector comprises a pair of diodes D₁, D₂, connected as a balanced rectifier to the two input circuits and to a common output. Thus there will be no direct current across the output when input signal is applied to only one of the inputs. The expression "product detector" or "coincidence detector" will be used herein to designate any arrangement similar to that of Fig. 4 which does not produce a characteristic output except when a signal is applied to each of two inputs simultaneously.

In Fig. 1, components derived from loop antenna 1 and sense antenna 5 pass through the early circuits of the receiver 4, together with essentially the same time delay and do not interact with each other to produce a new component from which the indicating voltage is derived until they reach detector 6. In Fig. 2, however, reference voltage from antenna 5 passes first through the receiver 4, is then converted to a low frequency in mixer 12, amplified in amplifier 14 and applied to modulator 2 where it interacts with signal from loop 1 to produce a new component (sideband) which passes through the receiver 4, emerging as a component of frequency f_0 from which is derived the indicating voltage in device 15. Hence modulator 2 itself serves the function of a product detector to which signal is applied directly from antenna 1 and indirectly from antenna 5 through elements 4, 12 and 14. Because of the time delay in the receiver circuits and in the beat-note circuits at 14, it is obvious that the major portion of a noise impulse intercepted at antennae 1 and 5 does not reach modulator 2 from antenna 1 and from amplifier 14 at the same time so as to cause output in receiver 2.

As explained in my copending application Serial No. 790,501, filed on even date herewith, the interaction of an impulse from antenna 1 with an earlier impulse from antenna 5 produces a component of frequency f_0 in the receiver output the phase relation of which, with respect to that of oscillator 13, is determined by the delay in receiver 4 and amplifier 14 and by the spacing of the impulses which is, for random noise, likewise random. Hence the polarity of the output of device 15 will be random also, consisting of a large amount of alternating components which are rejected by filter 10, and no unidirectional component which could be passed to terminals 11. As explained in said copending application also, the actual value of the D. C. component produced at terminals 11 by the effect of directional noise is e^{-ad} times as strong as it would have been without the action of the delay effect, where e is the base of the natural system of logarithms, a is the decrement of the tuned loop circuit, and d is the delay, in seconds, involved in traversing elements 4 and 14. Since

$$a = \frac{\pi f}{Q}$$

where f is the signal frequency in cycles per second and Q is the ratio of reactance to resistance in the loop tuned circuit, it is obvious that a relatively large product ad is obtained even for relatively small values of d , and a relatively large reduction in the effect of noise results. This results from the relatively large value of the decrement a in the usual loop circuit, and shows the advantage of combining the loop signal with the reference signal at the input of the receiver where the loop noise is still highly damped and decays to a negligible value before that from the sense antenna arrives, even after a relatively short delay. In fact, I have found that with the arrangements as disclosed in Fig. 2, the incidental delay of the receiver circuits is sufficient to reduce the noise effect as much as is normally required without the deliberate introduction of delay circuits at amplifier 14.

The phasing circuit 3, used in the conventional circuit of Fig. 1 to assure that the sidebands from modulator 2 can be detected as amplitude modulation in detector 6, is not necessary in the arrangement of Fig. 2 because the desired phase relation between the sideband component of frequency f_b and the beat frequency oscillator voltage can be obtained either by the introduction of phase shift in audio circuit 14 or by adjustment of the phase of the voltage from oscillator 13 applied to device 15. This has two advantages. One is the elimination of the design problem involved in applying a 90° phase shift in the low-level variable signal frequency circuit independent of tuning adjustment and without loss of signal or introduction of tube and circuit noise. The other advantage is that the natural quadrature phase relation between loop and sense antenna voltages existing without the use of circuit 3 is such that the sidebands from balanced modulator 2 are so phased with respect to the carrier from sense antenna 5 that the sum of the carrier and sideband signals in the receiver appears as a phase-modulated wave, the modulation sidebands of which are not so readily destroyed by limiting action due to overloading by noise as are those associated with amplitude modulation.

Some of the carrier signal from sense antenna 5, however, may be lost by overloading in the receiver. Fortunately, however, the signal from antenna 5 is large relative to that from loop 1 when the loop is near its null orientation and the action of the indicator or loop servo is most critical. As is well known, mixer 12 acts as a frequency translating device under the control of oscillator 13 and can be designed to minimize the effect of overloading so that it produces a component of frequency f_b from the signal even if the signal is weaker than the noise, whereas the effect of the weaker signal on the output of second detector 6, Fig. 1, is mostly lost in the non-heterodyne detector, especially if detector 6 is a high-level diode rectifier as is usually the case. One of the major functions of the selective circuit of amplifier 14, which is broadly tuned to the low frequency f_b of the beat note from 12, is to reject some of the noise from mixer 12 which might otherwise overload balanced modulator 2 and result in loss of directional sensitivity.

To aid in clarifying the operation of the circuit, the phase relations are traced as follows: The signal from the sense antenna may be expressed as $E_s = V_s \cos \omega_s t = V_s \cos \phi_s$ where E_s is the instantaneous strength of the sense antenna signal, V_s is its peak strength, ω_s is 2π times the signal frequency, and t is the time, in seconds, elapsed

since some arbitrary time when ϕ_a was zero. If this signal is applied to the first detector along with voltage from the usual high-frequency local heterodyning oscillator in the superheterodyne receiver given by $E_h = V_h \cos \omega t = V_h \cos \phi_h$, the output of the first detector will contain a component instantaneously proportional to the product of E_s and E_h . If $\omega_h < \omega_s$ (low-side injection), it is seen from the identity

$$2 \cos a \cos b = \cos(a+b) + \cos(a-b)$$

that the I. F. output of the first detector can be written

$$\frac{KV_s V_h}{2} \cos(\phi_s - \phi_h) \quad 15$$

where K is a detection coefficient, since it is only the lower sideband of the modulation process which is accepted by the I. F. circuits. The I. F. signal output of the receiver can then be written

$$E_{iL} = V_{iL} \cos(\phi_s - \phi_h - \phi_d) = V_{iL} \cos \phi_s \quad 20$$

where V_{iL} is determined largely by the receiver gain, and ϕ_d is the phase shift due to the delay in the receiver circuits, given numerically by $\phi_d = \omega_{is} d_{is}$, where ω_{is} is 2π times the frequency of the signal component in the I. F. circuit, and d_{is} is the delay of the receiver circuits at this frequency. If the beat frequency oscillator voltage from oscillator 13 is given by

$$E_0 = V_0 \cos \omega_0 t = V_0 \cos \phi_0 \quad 25$$

and if the beat frequency oscillator frequency is lower than that of the signal, the beat note output of mixer 12 is $E_m = V_m \cos(\phi_{iL} - \phi_0)$. The output of amplifier 14 is then given by

$$E_b = V_b \cos(\phi_{iL} - \phi_0 - \phi_a) = V_b \cos \phi_b \quad 30$$

where ϕ_a is the audio phase shift in circuit 14. The output of loop 1 when misoriented from the null direction in a given sense may be written

$$E_L = V_L \cos\left(\phi_s + \frac{\pi}{2}\right) \quad 35$$

since the loop voltage is in phase quadrature with the sense antenna voltage. The lower sideband output of the loop modulator will then be

$$E_{iLm} = V_{iLm} \cos\left(\phi_s + \frac{\pi}{2} - \phi_b\right) \quad 40$$

or

$$E_{iLm} =$$

$$V_{iLm} \cos\left(\frac{\pi}{2} + \phi_a + \phi_0 + \phi_h + \omega_{is} d_{is}\right) = V_{iLm} \cos \phi_{iLm} \quad 45$$

At the I. F. output of the receiver, this becomes

$$E_{iLm} = V_{iLm} \cos(\phi_{iLm} - \phi_h - \omega_0 d_0) \quad 50$$

where ω_0 is 2π times the beat frequency oscillator frequency, and d_0 is the delay of the receiver circuits at this frequency. This reduces to

$$E_{iLm} = V_{iLm} \cos\left[\phi_0 + \phi_a + \omega_{is} d_{is} - \omega_0 d_0 + \frac{\pi}{2}\right] \quad 55$$

Now $\omega_{is} - \omega_0 = \omega_b$, where ω_b is 2π times the frequency of the beat note. If the delay of the receiver circuits is substantially the same at the I. F. signal frequency as at the beat frequency oscillator frequency, then $d_{is} = d_0 = d_r$, and we have

$$E_{iLm} = V_{iLm} \cos\left[\phi_0 + \phi_a + \omega_b d_r + \frac{\pi}{2}\right] \quad 60$$

Since $\phi_a = d_a \omega_b$, where d_a is the delay of the audio beat-note circuit, this can be written

$$E_{iLm} = V_{iLm} \cos\left[\omega_0 t + \omega_b (d_a + d_r) + \frac{\pi}{2}\right] \quad 65$$

This is seen to be a component of the same frequency as the beat frequency oscillator voltage applied to mixer 12 but differing therefrom in phase by $\omega_b (d_a + d_r)$ radians due to delay, in addition to

$$\frac{\pi}{2}$$

radians due to the quadrature phase of the loop voltage. 10

A similar analysis shows that when the beat frequency oscillator frequency is higher than that of the signal, the component of the beat frequency oscillator frequency in the receiver output circuit is

$$E_{iLm} = V_{iLm} \cos\left[\omega_0 t - \omega_b (d_a + d_r) + \frac{\pi}{2}\right]$$

That is, the phase shift due to delay reverses sign on opposite sides of zero beat. 20

Now the product detector at 15 requires the two components applied to its input to be in phase to produce an indicating voltage of the correct sense. If they are 180° out of phase the sense will be reversed, and if in quadrature, the sensitivity will be zero. Since this phase relation depends on the beat note and therefore on the receiver tuning, there is provided a tuning indicator 16 actuated by the beat-note output of selective amplifier 14. When the receiver is tuned for a maximum indication on tuning indicator 16, the beat note will be of the correct frequency as determined by the peak frequency of amplifier 14. This frequency can be chosen so that $\omega_b (d_a + d_r)$ is an odd multiple of

$$\frac{\pi}{2}$$

so as to compensate for the quadrature phase relation of the loop voltage. However, the sense of the indication will then be opposite for the same beat-note frequency on opposite sides of zero beat. Hence I prefer to make the quadrature correction by means of phasing network 17 which puts the beat frequency oscillator voltage from oscillator 13 applied to device 15 in quadrature with this same voltage that is applied to mixer 12. The beat note is now chosen so that

$$\omega_b (d_a + d_r)$$

is a multiple of π , and the sense will be the same on opposite sides of zero beat. 50

Referring to Fig. 3, there is shown a modification of the system of Fig. 2, the parts of Fig. 3 which are the same as those of Fig. 2 being designated alike. In Fig. 3, beat note f_b in the output of mixer 12, resulting from the mixing of the intermediate frequency signal f_s and the beat frequency f_0 from oscillator 13, is amplified in the amplifier 14 which is tuned by the network 18, 19, to the frequency f_b . The beat note f_b in the output of amplifier 14 is periodically reversed in phase by a switching device comprising the movable contact arm 20 and the associated spaced contacts 21, 22, the arm 20 being oscillated by a cam 23 by means of a suitable motor 24. Consequently, the component in the output of receiver 4 of frequency f_b which reacts in the product detector 15 with the beating frequency from oscillator 13, is also reversed in phase periodically. Thus, the output of detector 15 due to this component, is an alternating current of the frequency determined by the frequency of operation of switch arm 20 rather than a direct current increment. It will be observed that the product

detector 15 comprises a conventional plural grid tube 25 which may be of the so-called pentagrid converter type comprising the cathode 26, first control grid 27, shield grids 28, 29, second control grid 30, suppressor grid 31, an output plate or anode 32. The component f_0 in the output of receiver 4 is applied to control grid 27, while the beating frequency f_0 from the oscillator 13 is applied to the control grid 30. The alternating current component in the output of tube 25 is applied to the phase inverter tube 33 and thence to the push-pull amplifier tubes 34, 35. The push-pull output of tubes 34 and 35 is applied to the movable switch arms 36, 37, which are operated in unison with the arm 20 above described. Each of the switch arms 36 and 37 has an associated set of spaced contacts which are connected to the filter circuit 10 as shown. The switch arms 36 and 37 with their associated fixed contacts constitute a mechanical rectifier which is driven in synchronism with the switch arm 20 to produce a direct current signal that is applied to the filter 10. This direct current component, after being filtered in device 10, is amplified by the direct current amplifier, comprising amplifier tubes 38, 39, whose output is connected to the output terminals 11. Terminals 11 can be connected to any suitable bearing indicator or servo-control device in the event that the direction finder is of the automatic type.

One of the advantages of the embodiment of Fig. 3 over that of Fig. 2, is that the components of switch frequency controlled by cam 23, are readily selected from the output of device 15 and are readily amplified, whereas the selection of a small direct current increment and its amplification as in the system of Fig. 2, involves considerable difficulty in balancing-out small direct current changes caused by changes in tubes, voltage, temperature and the like.

While certain particular embodiments have been described herein, it will be understood that various changes and modifications may be made therein without departing from the spirit and scope of the invention.

What is claimed is:

1. A direction finder arrangement of the type having a loop antenna and a sense of direction antenna the signals from which are to be combined to produce a direction indicating voltage, a radio receiver to whose input the signal from said sense of direction antenna is applied, a source of local beating frequency, means to heterodyne the signal from the output of said receiver with said beating frequency to produce a beat note, a balanced modulator which is fed by the signal from said directional antenna and by said beat note, a time delay circuit through which said beat note passes before reaching said modulator, means to apply the modulated signal from said modulator to the input of said receiver, and circuit arrangements for producing said indicating voltage from only those components in the receiver output which are of the same frequency as said beating frequency.

2. A direction finder arrangement according to claim 1 in which the last-mentioned circuit arrangements include a product detector having a pair of input circuits, means to feed one input circuit from the output of said receiver, and means to feed the other input circuit with said beating frequency.

3. A direction finder arrangement according to claim 1 in which said time delay circuit includes

an audio frequency amplifier tuned to said beat note.

4. A direction finder arrangement according to claim 1 in which said radio receiver is of the superheterodyne type and the said signal which is heterodyned with said beating frequency is an intermediate frequency carrier from said receiver.

5. In an arrangement of the type described, means to derive two carrier signals of the same frequency f_s one of which is a directional signal and the other a sense of direction signal, a superheterodyne radio receiver, means to apply the sense of direction signal to the input of said receiver, a balanced modulator whose output is also applied to the input of said receiver, an oscillator for generating a local beating frequency f_0 , a mixer device, means to apply a selected intermediate frequency from said receiver and also said beating frequency to said mixer to produce a beat note of frequency $f_b = f_s - f_0$, means to apply said beat note and said directional signal to said balanced modulator to produce in the output of said receiver a frequency $f_s - f_b$, a product detector having a pair of input circuits, means to apply to one input circuit said frequency $f_s - f_b$, means to apply to the other input circuit said beating frequency f_0 , a pair of output terminals to which a direction signal responsive device is to be connected, and a filter circuit connected to the output of said product detector for passing only the uni-directional components thereof to said output terminals.

6. An arrangement according to claim 5 in which a phasing control circuit is connected between said beating oscillator and said product detector to maintain the frequency f_0 from the beating oscillator and the frequency $(f_s - f_b)$ from said receiver at phase quadrature with respect to each other.

7. An arrangement according to claim 5 in which means are provided for regularly and recurrently reversing the phase of the said beat note, and means are provided for mechanically rectifying the signal from said product detector in synchronism with said recurrent phase reversal.

8. An arrangement according to claim 5 in which the output of said product detector is connected to an alternating current amplifier and thence to a mechanical rectifier, said rectifier being connected to said output terminals through said filter.

9. An arrangement according to claim 5 in which said beat note is applied to the switch arm of a reversing switch for reversing the phase of the beat note regularly and recurrently at a pre-determined rate, said product detector is connected to an alternating current amplifier whose output is applied to the switch arm of a mechanical rectifier, and motor driven cam means are provided for operating both said switch arms in synchronism.

10. The method of producing a direction finding indication voltage by combining two received voltages each of a carrier frequency f_s , one of which is a direction signal and the other is a sense of direction signal, which comprises mixing the sense of direction signal with a local generated beating frequency f_0 to produce a beat note frequency f_b , modulating the direction signal with said beat note frequency to suppress the frequency f_s while generating a side band frequency $(f_s - f_b = f_0)$, and applying the said beating frequency and the said side band frequency $(f_s - f_b = f_0)$ to a circuit which produces an out-

put only in response to the timed coincidence of two applied input voltages.

11. The method according to claim 10 in which the said beat note is subjected to a time delay before modulating the direction signal.

12. The method according to claim 10 in which said output is subjected to a filter action to filter out all except the uni-directional components.

13. A direction finder arrangement of the kind employing a directional antenna and a sense of direction antenna which latter antenna feeds a radio receiver and the signal from the directional antenna is subjected to modulation by a separate low frequency, a local source of beating frequency, means to mix the beating frequency with the signal from the receiver to produce said low frequency, means to subject said low frequency to a time delay, means to modulate the signal from said directional antenna by said time delayed low frequency, means to apply the said modulated signal to the input of said receiver, means to se-

lect from the output of the receiver a frequency equal to said beating frequency, and a product detector which is fed with said beating frequency and said selected frequency to produce a bearing indication signal voltage.

14. A direction finder arrangement according to claim 13, in which the means for subjecting said low frequency to a time delay comprises a selective low frequency amplifier having substantial time delay between its input and output signals.
